UNITED STATES PATENT OFFICE.

FRANK A. ROBBINS, OF WORCESTER, MASSACHUSETTS.

TROLLEY DEVICE.

No. 908,161.

Specification of Letters Patent.

Patented Dec. 8, 1908.

Application filed November 11, 1907. Serial No. 401,536.

To all whom it may concern:

Be it known that I, FRANK A. ROBBINS, a citizen of the United States, residing at Worcester, in the county of Worcester and State of Massachusetts, have invented a new and useful Trolley Device, of which the following is a specification.

This invention relates to a trolley for electric cars.

The principal objects of the invention are to provide an improved way of supporting the trolley harp and wheel in such a manner that they will be movable with respect to the trolley poles and will be pressed up therefrom by a direct spring pressure toward the trolley wire when the wheel is on the wire and yet the motion of the harp with respect to the trolley pole cannot possibly result in a binding action between these two elements; also to provide for efficiently holding the trolley harp in proper position and at the same time preventing it from moving far out of the vertical; to provide means whereby the trolley wire will be prevented from passing into the space between the sides of the harp and the wheel and to hold the wheel on the harp in case of any accident such as the loss of the shaft on which the wheel turns; and generally, to improve the construction and operation of electric car trolleys of this character.

Further objects and advantages of the invention will appear hereinafter.

Reference is to be had to the accompanying drawing which shows certain preferred embodiments of the invention and in which,

Fig. 1 is a side elevation of the same. Fig. 2 is a similar view on an enlarged scale showing the upper part of the device. Fig. 3 is an end elevation of the same. Fig. 4 is a view similar to Fig. 2 showing certain modifications, and Fig. 5 is a plan of the lower part of the device showing the same.

In the form of the invention illustrated, the device is supported on a base 10 mounted in fixed position on the top of the car in any usual way. This base is provided with a ball-race 11 on its upper surface in which bearing balls 12 are located and on which is supported a turret 13 adapted to swing on the vertical axis through the center of the ball race. This turret is provided with one or more lugs 14 at the front and with a projection 15 at the rear. On this projection is mounted a shaft 16 which constitutes the axis about which a trolley pole holder 17 is

adapted to turn. Between the holder 17 and the lug 14 are one or more springs 18. These springs are, or may be, of any usual construction put in position and adjusted in any usual way, but instead of being located in the usual manner, they are so placed that when the holder 17 is turned downwardly about its pivot to let the trolley pole 20 rest on the top of the car, the springs pass through the point of greatest tension and are then located below the axis 16 so that while they are still under some tension, they are not then under their maximum tension. Under ordinary circumstances, the springs which are used at this point are always under the heaviest tension to which they are ever subjected when the cars are out of use in the car barn, which obviously has a most important bearing on the length of life of the springs. By this invention the life of the springs is necessarily prolonged on account of the fact that they are not under heavy tension at this time, and when they are in use on the road they are not under any more tension than is the case with the present construction. Another advantage of this construction is that after the springs pass the point of greatest tension, they will act to pull the trolley pole down on the car and thus it will not be necessary to provide any means for tying the pole down and there will be nothing which can get out of order and let the pole fly up and possibly strike overhead wires and cause damage.

In order to provide for gently limiting the upward movement of the trolley pole in case the trolley gets off the wire, a spring buffer 21 is provided on the projection 15. This acts in an obvious manner, as indicated in Figs. 1 and 5.

On the upper end of the pole 20 a trolley harp holder 25 is supported. This holder is designed to be off-set downwardly from the pole so that its upper bearing surface 26 may be substantially horizontal when the device is in use. In order to accomplish this result, the holder is provided with an extension 27 having an end 28 which fits the end of the trolley pole in any desired way and is secured thereto, this end being in line with the trolley pole. The holder is provided with a downwardly flaring passage 29 through which a rod 30 is adapted to pass. A spring 31 surrounds the rod and rests on the bearing 26 engaging the bottom surface of the trolley harp 32. A cotter-pin or the like 33

passes through the rod 30 and limits the upward motion of this rod caused by the spring. It will be obvious that with this construction, the spring acts to lift the harp and the opening 29 allows the rod to move through it and is of such a shape as to prevent any binding thereof if its motion is not strictly vertical.

In order to prevent the rod from turning, it is provided with a longitudinal slot 34 10 and a projection 35 extends into the opening 29 and into the slot 34. This projection is shown in the form of a removable screw but that is not a necessary construction. In order to further assist this operation and prevent the harp from turning and also to hold it in substantially a vertical position, a pair of links 40 are pivotally mounted at the upper end of the extension 27 so as to freely swing and are provided with slots 41 in their 20 opposite ends through which projections or the like 42 on the harp extend. It will be seen that this provides for preventing any great inclination of the rod 30 and allows sufficient play for ordinary purposes and especially to provide for rounding curves. Also it assists in holding the harp from turning too far and furthermore, it has another important function in that the links 40 being inclined, cut off the space between the 30 rod 30 and the extension 27 so that if the trolley does get off the wire, these links 40 will receive the cross wire and let it run up over the wheel instead of allowing it to catch in the depression. Another form of 35 these links is shown in Fig. 4 in which they appear as a U-shaped strap 45 having a slot and operating in about the same way. In this case also another modification is shown in that at the upper end of the extension 27 40 are a pair of flanges 46 which can be clamped together around the end of the pole instead of being fastened in the usual way, as indicated in Fig. 2.

Any ordinary form of harp may be used 45 with this invention.

The cord by which the conductor controls the trolley may be fastened in an eye 48 or in an eye 49, one being on the harp and the other on the holder.

50 In order to provide for preventing the wire from getting between the wheel and the harp and to prevent accidental displacement from the harp, the harp is provided with a pair of inwardly extending lips 50. As the 55 harp is held in vertical position, these lips can be made on the top thereof so as to be sure to catch a wire 51 if the trolley runs off and prevent its passing down between the wheel and harp. In order to accomplish 60 this, the lips preferably extend inwardly so far that the distance between them is less than the width of the flange of the trolley wheel 52. In order to provide for this and yet permit the wheel to be applied and removed, the wheel has a pair of slots 53

through which the lips may be passed. It will be seen, therefore, that the wire is not only prevented from getting down into this space but also the wheel is prevented from being accidentally removed in case the shaft 70 should become loosened in operation or in an accident.

The trolley-base which I have shown and described is not claimed herein as it forms the subject of a separate divisional application.

While I have illustrated and described certain preferred forms of the invention, I am aware that many modifications may be made therein by any person skilled in the art without departing from the scope of the invention as expressed in the claims.

Having thus fully described my invention, what I claim and desire to secure by Letters-Patent is:—

1. As an article of manufacture, a trolley wheel having opposite, substantially continuous, circular outwardly-flaring flanges, each provided with a slot in the outer side of the outer edge thereof located substantially perpendicular to the axis of the wheel, said slots being located opposite each other, whereby said wheel may be applied to and removed from a trolley harp having integral inwardly-projecting flanges. 95

2. The combination of a trolley harp having inwardly extending lips, with a wheel therefor, the flanges of which are wider than the distance between the lips, and are provided with slots to permit the application and removal of the wheel. 100

3. A trolley harp having lips extending inwardly at the top thereof and provided with a wheel mounted on the harp, its flanges being wider than the space between 105 said lips, said flanges having slots, whereby the wheel may be removed or applied without tipping the wheel with respect to the harp.

4. In a trolley, the combination of a harp, a rod extending downwardly therefrom, a holder for the rod having a bearing at the top and a downwardly flaring perforation therethrough, a spring supported on said bearing and surrounding said rod, and means on the rod engaging the under side of the holder for limiting the upward motion of the rod therein. 110

5. In a trolley, the combination of a harp, a rod extending downwardly therefrom, a 120 holder for the rod having a bearing at the top and a downwardly flaring perforation therethrough, a spring supported on said bearing and engaging said harp, means on the rod engaging the under side of the 125 holder for limiting the upward motion of the rod therein, and means for preventing said rod from turning.

6. In a trolley, the combination of a harp, a rod extending downwardly therefrom, a 130

- holder for the rod having a bearing at the top and a downwardly flaring perforation therethrough, a spring supported on said bearing and surrounding said rod, said 5 holder having a projection by which it may be secured to a trolley pole, and means on the holder and also on the projection for preventing the harp from turning.
7. In a trolley, the combination of a harp, 10 a rod extending downwardly therefrom, a holder for the rod having a downwardly flaring perforation therethrough, a spring supported on said holder and supporting said harp, a link movably connected with 15 the holder and loosely connected with the harp for preventing the harp from turning and for holding the harp substantially in vertical position on the holder, whereby said bearing will guide the rod on the harp 20 but will not cause the same to bind when it is slightly out of vertical position.
8. In a trolley, the combination of a holder

having a flaring passage therethrough, a trolley harp, a rod extending through said passage and connected with the harp, whereby the rod may be swung out of a vertical 25 position without binding in said passage.

9. In a trolley, the combination of a holder having a flaring passage therethrough, a trolley harp, a rod extending through said 30 passage and connected with the harp, whereby the rod may be swung out of a vertical position without binding in said passage, and a projection in said passage on the holder, said rod having a slot for receiving 35 said projection to hold the rod against turning.

In testimony whereof I have hereunto set my hand, in the presence of two subscribing witnesses.
